UNITED STATES PATENT OFFICE

116,996

DESIGN FOR A FONT OF TYPE

Warren Chappell, New York, N. Y., assignor to American Type Founders, Inc., Elizabeth, N. J., a corporation of New Jersey

Application January 11, 1939, Serial No. 82,296

Term of patent 7 years

To whom it may concern:

Be it known that I, Warren Chappell, a citizen of the United States, residing at New York, county and State of New York, have invented a new, original, and ornamental Design for a Font of Type, of which the following is a specification, reference being had to the accompanying drawing, forming part thereof.

The drawing is a face view of a font of type showing my design.

The font of type of the present invention is characterized by the ribbon-like appearance of the character elements, the type of the present font conveying an impression of character depth and, by optical illusion, the angle of view appearing to change with respect to certain of the characters.

I claim as my invention:

The ornamental design for a font of type, as shown and described.

WARREN CHAPPELL.
